UNITED STATES PATENT OFFICE

ALLISTER S. MITCHELL, OF DETROIT, MICHIGAN

BAT REELING MACHINE

Application filed February 11, 1929. Serial No. 339,038.

The invention forming the subject matter of this application relates to bat reeling machines.

Heretofore the practice in connection with the packing of bat has been to fold the bat in zigzag layers in a suitable box, from which box the bat was unfolded layer after layer and fed into stuffing tools or the like. This method of handling the bat proved to be unduly expensive and difficult in respect to proper packing or folding. The invention contemplates the winding of the bat on a reel to facilitate its introduction into a stuffing tool.

15 It is the primary object of the invention to provide a device by means of which the bat is efficiently wound into a roll, and in which the spiral winding of the bat is automatically accomplished.

23 Another object of the invention is the provision of a bat reeling machine in which the feeding means to the reel are automatically reciprocated on a path parallel with the axis of the reel, said reciprocation being caused by 25 the rotative movement of the reel, whereby the spiral winding of the bat on the reel spindle is readily achieved.

Another object of the invention is the provision of a mechanism by which the position 33 of the feeding means to the reel machine is automatically adjusted in accordance with the increasing diameter of the roll during the winding of the bat on the reel.

Another object of the invention is the provision of means for automatically securing 35 the feeding means in such position as to assure non-interference with the manipulation of the reel after the completion of the winding of the bat thereon.

40 Another object of the invention is the provision of a bat winding or reeling machine in which the reel is rotated by rotating drums, upon which the reel rests and with which the periphery of the reel is in frictional engagement, clutches being provided for supporting the reel in position with freedom of rotative movement, said clutches being supported in turn with freedom of vertical movement relatively to the rollers thereby allowing the raising of the reel in accordance with

the increase of the roll diameter during the winding of the bat; thus the periphery of the roll of bat formed on the reel frictionally contacts with the rollers at all times during the winding.

55 Another object of the invention is the provision of a feed horn through which the bat is fed, said horn being spaced from and capable of reciprocable movement parallel with the axis of the reel, the reciprocation thereof being effected by transmission means connecting the horn to one of the clutches which axially supports the reel.

Another object of the invention is the provision of resilient means for urging said 65 horn into operative position relatively to the reel and of means to move said horn away from the reel, said latter means being actuated by the raising of the reel clutches, so that the feed horn is adjusted to a proper 70 operative position relative to the periphery of the reel at all times while the diameter of the roll thereon changes in accordance with the length of bat wound thereon.

75 Other objects of the invention are to provide a bat reeling machine of the character described that will be superior in its point of simplicity, inexpensiveness of construction, positive of operation, and of a high standard in its general efficiency.

80 In this specification, and the annexed drawings, the invention is illustrated in the form considered to be the best, but it is to be understood that the invention is not limited to such form as it may be embodied in other forms; 85 and it is also to be understood that in and by the claims following the description, it is intended to cover the invention in whatsoever form it may be embodied.

85 The invention is clearly illustrated in the 90 accompanying drawings in which

Figure 1 is a top plan view of the machine;

Figure 2 is a side elevation of the machine, viewed in the direction of the arrow 2, Figure 95 1;

Figure 3 is a side elevation of the machine, viewed in the direction of the arrow 3, Figure 1;

Figure 4 is a sectional view of the machine, 100

the section being taken on the line 4—4 of Figure 1;

Figure 5 is a rear view of the machine, showing the clutches in their uppermost position which they occupy at the time when the roll is completely wound;

Figure 6 is a front view of the machine, showing the clutches in a slightly raised position, and indicating in dotted lines the reel 10 releasing position of one of the clutches and of the arm upon which the said clutch is mounted;

Figure 7 is a plan view of the feed horn showing the width adjusting means thereof;

15 Figure 8 is a rear view partly in section of the feed horn, the section through the upper half thereof being taken through the line 8—8 of Figure 7;

Figure 9 is a detail view of the feed horn 20 and part of the reciprocating and adjusting mechanism therefor, the dotted lines indicating the position of the feed horn in its position when the reel is fully wound;

25 Figure 10 is a fragmentary detail view of the protruding pin in the chain of the horn reciprocating mechanism, showing the roller on the pin in section;

30 Figure 11 is a sectional detail view of the fixed section of the horn and the support therefor, the section being taken on the line 11—11 of Figure 9; and

35 Figure 12 is a fragmentary sectional view of the fixed section of the feed horn and the reciprocating support to which the horn is 100 adjustably secured, the section being taken on the line 12—12 of Figure 9.

40 For a more comprehensive and clearer understanding of the invention reference may now be had to the accompanying drawings in which similar reference characters designate similar parts throughout the various figures described above taken together with the following detail description.

45 By the word bat as used in the specification is meant a sheet of cotton or other fibrous material after it leaves the batting machine. The bat is spirally wound on to a reel by the machine herein described which comprises a reel rotating and driving mechanism designated in its entirety by the letter A and a bat adjusting mechanism denoted by the letter B supported by supporting frame 6 as shown in the drawings. The device is operated by electric motor 7 which is connected 50 through suitable reduction gearing to a transmission 8. The said transmission is composed of two sheaves 9 over which passes a chain belt 11. Each sheave is formed by two substantially circular discs having inwardly 55 extending conical hubs tapering toward each other and are slidably keyed on shafts 12 which are supported in frame members 13 and disposed in parallel spaced relation to each other. The hubs of the sheaves 9 are 60 capable of a slight sliding movement on the

shaft 12 for the purpose of being moved toward or away from each other. Between the hubs of the sheave 9 and the inner face of the frame members 13 are disposed adjusting bars 14 having apertures therein and in slidable 70 engagement with respective shafts 12. The adjusting bars 14 are parallel with the frame members 13 and are spaced therefrom. The movement of the adjusting bars 14 for drawing the respective sections of sheaves 9 toward each other or forcing them away from each other is accomplished by means of adjusting screw 16 which has screw-threaded engagement with the bars 14. Bar 15 may be 80 provided with a right hand and left hand thread for adjusting the bars toward and away from each other. For limiting the sliding movement of the sections of the sheaves 9 on shafts 12. Pivot pins 10 are suitably supported by bar 15 for pivotal movement thereabout of bars 14.

85 From the foregoing it will be readily seen that adjusting bars 14 may be moved toward or away from the sheaves 9 at their respective ends by the rotation of screw 16 according to the direction of rotation of said screw. When the bars 14 are moved toward each other at their upper ends the opposed sections of the upper sheave 9 are forced toward each other, thereby forcing the chain belt 11 outwardly toward the periphery of the sheave, thus increasing the diameter of that portion of the sheave engaged by the chain and the movement of the bars 14 and the sections of the discs forming the lower sheave away from 95 each other causes the chain belt to engage the sheave at a point closer to the center of the sheave thereby frictionally engaging the sheave at a point of smaller diameter which decreases the speed of the rotation of the upper sheave.

100 The inward movement of the bars at their upper ends under the action of adjusting screw 16 will result in the outward movement of the lower ends of the bars and a separation or movement away from each other of the sections forming the lower sheave, thereby decreasing the diameter of the sections of the sheaves engaged by the chain belt, thereby 105 decreasing the speed of rotation of the lower sheave thus the ratio of the sheave diameter and the driving speed of the winding mechanism herein set forth is efficiently and accurately regulated.

110 The shaft 12 of the upper sheave 9 extends beyond the frame 6 and carries a sprocket 17 thereon. In bearings 18 on the top of the frame 6 are journaled stub shafts 21 on the opposite ends of drum 23 and stub shaft 21 115 on one end of drum 22. On stub shaft 21 of drum 22 is keyed or otherwise non-rotatably secured sprocket 24 which is in alignment with sprocket 17 and in driving connection therewith by means of a chain belt 26. The adjacent stub shaft 21 of the drum 23 is pro- 120

vided with a sprocket 27 non-rotatably secured thereto and connected with driving sprocket 28 on the stub shaft 21 of drum 22 by suitable chain belt. The drums 22 and 23 are thus rotated in the same direction.

The reel rotating and driving mechanism is completed by the provision of two clutches 31 and 32 adapted to engage a reel tube 30, the tube 30 being shown in dotted lines in side of a reel of bat in Fig. 4. The clutches 31 and 32 have corrugated faces forming cutting edges for engaging the ends of the tube 30 when forced therewithin and are provided with short shafts 33, which shafts are rotatably supported in bearings on the upper extremities of arms 34. Arms 34 are pivotally secured at their respective lower ends to the opposite ends of a horizontal bar 36, extending across the supporting frame 6, below the drums 22 and 23 and substantially in parallelism therewith. In order to maintain the arms 34 in a vertical position, a yieldable connection is provided therebetween by spring 38 interposed between the ends of rods 37 which are secured to the arms above the pivotal points thereof.

Inasmuch as the horizontal bar 36 is not supported on the supporting frame 6, the clutches 31 and 32 are permitted free reciprocal vertical movement with relation to drums 22 and 23. The clutches are disposed between the adjacent peripheries of the drums 22 and 23. When a reel tube 30 is placed on the clutches 31 and 32 and gripped therebetween, it will rest between the drums 22 and 23 and will be frictionally engaged thereby, which engagement will cause the rotation of the tube 30, and the roll formed thereon when the drums 22 and 23 are rotated by the mechanism heretofore described. The winding of the bat on the tube will cause an increase of the diameter of the tube and bat by the increasing thickness of the bat being wound thereon, thereby raising tube 30 relative to the drums 22 and 23, arms 34 and bar 36 will be lifted therewith thus combining their weights to hold the tube in frictional engagement with drums 22 and 23. The arms 34 are guided in their vertical movement by guides 40, formed by two parallel plates extending beyond each side of the frame 6 and contacting with the arms 34 respectively.

It will be noted that the insertion and removal of the tube from the clutches 31 and 32 is accomplished by rocking the arms 34 outwardly around their pivot, thereby withdrawing the clutches from engagement with the tube 30, whereby the insertion or removal of a reel is permitted.

The drums 22 and 23 as shown in Fig. 4 are rotated in a clockwise direction which will result in tube 30 being rotated in a contra clockwise direction. The bat is drawn between the drum 22 and the tube 30, and is

wound around the tube, thus bringing the bat wound on the tube into frictional engagement with the drums 22 and 23 resulting in the rotation of the tube 30 and the clutches 31 and 32, and continuously draws the bat 70 into the machine, whereby a substantially automatic feeding is accomplished. In order to evenly distribute the bat throughout the whole length of the roll it is necessary to wind the bat around the reel spirally. This 75 spiral winding is accomplished by reciprocal movement of the bat feeding horn in parallelism with the axis of tube 30, the reciprocal movement of the horn being synchronized with the rotation of the tube. 80

The proper spiral winding of the bat is performed by the feed mechanism and the automatic adjusting mechanism B. The feed mechanism in its entirety is supported on brackets 41 and 42 on frame 6 in spaced 85 parallel alignment with drum 22. The brackets 41 and 42 being in alignment with each other are adapted to fixedly support two parallel rods 43 in vertical alignment with each other. On the bracket 41 is a bearing member 44 having an elongated slot 46 therein in which a sprocket 47 is adjustably rotatably secured. To bracket 42 is adjustably secured a bearing bracket 48 in which is rotatably mounted a shaft having sprockets 95 49 and 51 fixedly mounted thereon on the opposite sides of the bearing bracket 48. The sprockets 47 and 49 are connected to each other by means of a sprocket chain 52.

On the rods 43 is slidably supported a carriage 53 in a substantially vertical position. Said carriage has an elongated vertical slot 54 therein. A pin 56 carried by the sprocket chain 52 is extended beyond the plane of the links thereof and has a roller sleeve 57 rotatable thereon for engaging the slot, the free end of the pin 56 being threaded to receive a retaining nut 58 thereon.

Upon the carriage is adjustably mounted a feed horn denoted in its entirety by the numeral 59. When the sprocket 49 is rotated it will cause the rotation of the sprocket 47 and the passing of the sprocket chain 52 therearound. The chain 52 being connected to the carriage 53 by said pin 56 will advance the carriage therewith and the feed horn 59 secured thereto. When the carriage 53 reaches the limit of its movement in either direction the pin 56 is carried with the link of the chain 52 around the respective sprocket, 115 whereby it is caused to slide in the elongated slot 54 either downwardly or upwardly, depending on the direction of the chain movement and on the end at which the carriage is positioned at the time. The pin 56 after being carried around the respective sprocket is moved with the link of the chain 52 away from said sprocket, whereby the carriage movement is also reversed toward the opposite sprocket. Thus the carriage 53 and the 120

125

130

feed horn 59 secured thereto are continuously reciprocated in parallelism with the reel tube 30. The bat fed through the feed horn 59 is thus advanced throughout the length of the reel, by thus feeding the bat the spiral winding of the bat is uniformly effected throughout the full length of the winding.

The aforesaid reciprocating movement of the feed horn 59 is performed in synchronism with the rotation of the reel by transmitting rotary movement to the sprocket 51 from one of the clutches 32 by a bevel gear 61 on short shaft 33 in mesh with a companion bevel gear 62, as shown in Figure 6, the gears are maintained in intermeshing position by a gear housing 63 supported on the short shaft of the clutch 31.

An adjustable drive shaft 64 upon which the gear 62 is mounted extends substantially at right angles to the clutch shaft 33 and through a wall of the housing 63. Shaft 64 has a universal connection to shaft 66, the latter being rotatably mounted in a bearing 67 on the bearing bracket 48. On the end of the shaft 66 is mounted a sprocket 68 connected by sprocket chain to the sprocket 51. Through the aforescribed secondary driving mechanism rotation is transmitted from the clutch 32 to the sprocket 51, which causes the rotation of the sprocket 47, thereby reciprocating the carriage 53 and the feed horn 59 secured thereto in synchronism with the rotation of the clutch 32. It is to be noted that the universal connection of the driving shaft 64 allows the transmission of movement to the feed mechanism at all times regardless of the position of the clutches 32, which is raised by the increasing diameter of the bat roll as heretofore set forth.

When the bat is spirally wound on the reel the increase of the roll diameter thereon would cause the reduction of the clearance between the outer periphery of the bat roll and the discharge end of the feed horn 59. Inasmuch as it is desirable to maintain a substantially constant clearance between the periphery of the bat roll and the feed horn 59, the feed horn is mounted with freedom of adjustment in a direction transverse to the axis of the tube 30, and an adjusting mechanism is provided for effecting this adjustment in accordance with the diameter of the bat wound on reel tube 30.

The adjustable mounting of the feed horn 59 is clearly illustrated in Figures 9, 11 and 12. The feed horn 59 is attached to a base 71, the bottom of the latter having a dovetail tenon 72 thereon extending longitudinally relative to the feed horn 59. The carriage 53 has a dovetail mortise 73 in the top thereof, complementary to the dovetail tenon 72 and extending transversely to the rods 43. The top of the carriage 53 is inclined outwardly and upwardly relative to the horizontal axis of the reel tube 30, whereby the

sliding of the base 71 on the carriage 53 will cause not only the horizontal spacing of the feed horn from the reel but also a corresponding vertical spacing, thus allowing the same tangential feeding of the bat above the reel tube 30 at all times.

The base 71 has a yoke 74 extending downwardly from the end thereof adjacent to the reel. On the frame 6 is journaled a rocking shaft 76 as shown in Figures 1 and 4. Adjacent to the opposite sides of the frame 6 are two levers 77 fixedly mounted on the rocking shaft 76 and are bent toward the drum 22 at their upper portions, which permits of the reciprocal movement of the yoke with relation to the rod 78; the rod 78 is positioned within the yoke 74 as the feed horn is moved backwards and forwards on rods 43. However, the adjustment of the feed horn 59 transversely to the carriage 53 is readily accomplished by the to or fro rocking of the shaft 76, whereby the levers are rocked, the movement of the levers 77 being transmitted to the base 71 by the coaction of the rod 78 and the yoke 74.

For the purpose of rocking the rockshaft 76 in synchronism with and by the vertical movement of the clutches 31 and 32, I provide a shaft 79 journaled on the frame 6, the ends of the shaft 79 protruding beyond the sides of the frame 6, as shown in Figure 6. At each end of the drum 23, and on the respective stub shaft 21 thereof, is loosely mounted a sprocket 81 freely rotatable on the respective stub-shaft 21. On the outer ends of the shaft 79 are fixedly secured levers 82, said levers being of arcuate shape and having grooves in the outer peripheries thereof. To the end of each lever 82 is secured the end of a chain 83, which chain is positioned around the respective sprockets 81. The other end of the chain 83 is attached to the horizontal bar 36 at a point adjacent to the pivotal connection of the respective arms 34. The weight of the tube on the clutches 31 and 32 and the weight of the arms 34 and the bar 36 have a tendency to maintain the levers 82 in the position shown in Figures 2 and 4. Operative connection between the shaft 79 and the rocking shaft 76 is established by a lever arm 84 fixed on the rocking shaft 76 and connected to the shaft 79 by a chain 86. The end of said chain 86 is secured to the periphery of the shaft 79 in the manner shown at 87 in Figure 4. The lever arm is held in its initial position by a tension spring 88, the ends of which are attached to the frame 6 and to the lever arm 84 respectively. The tension of the spring 88 further aids in maintaining the lever 82 in the position corresponding to the lowermost position of the clutches 31 and 32.

In order to cause the turning of the shaft 79, when the reel tube 30 is lifted, a counterweight 89 is suspended from the shaft 79 so

as to exert a turning movement on the shaft 79 counteracting the action of the spring 88. The counterweight 89 is made of a rod substantially the length of the frame 6. Adjacent to the opposite ends of said counterweight 89 are attached suspending chains 91 secured into the grooved periphery of pulleys 92, which pulleys are in turn fixedly mounted on the shaft 79. The suspending chains 91 are of such length and are so secured to the respective pulleys 92 that when the reel tube is in its lowermost position the chains 91 nearly encircle the whole circumference of the pulleys 92 as shown in Fig. 4. It is to be understood that the action of the spring 88 and the weight of the clutches 31 and 32 and of the arms 34 and crossbar 36 are sufficient to normally counteract the turning movement of the counterweight on the shaft 79. Thus the lifting action of the bat, wound on the periphery of the reel, upon the clutches 31 and 32 is greatly facilitated, and an automatic return of the mechanism to the position shown in Figure 4 is assured. The same lifting action causes the turning of the shaft 79, whereby the chain 86 is unwound from around the shaft 79 causing a movement of the lever arm 84 against the action of the spring 88. The movement of the lever arm 84 rotates the rocking shaft 76 thus swinging the levers 77 away from the reel tube 30, which lever movement transmitted through the rod 78 and yoke 74 to the base 71 effects the sliding of the base 71 on the top of the carriage 53, thereby adjusting the position of the feed horn 59 relative to the periphery of the bat reel in accordance with the increase of the reel diameter. Hence the clearance of the discharge end of the feed horn 59 from the periphery of the bat reel is maintained substantially constant.

It is desirable to maintain the feed horn 59 in an out of way position while the completed bat roll is removed from the clutches 31 and 32; therefore dogs 93 are secured to the front wall of the frame 6 opposite the ends of the counterweight 89. The ends of the counterweight are reduced in diameter as at 94. When the bat roll, shown in dash and dot lines, Figure 4, and denoted by the numeral 96 reaches its maximum diameter, then the adjusting mechanism heretofore described assumes the position indicated in dotted lines in Figure 4, which brings the counterweight 89 below and in engagement with dogs 93. The dogs are so formed as to engage the reduced ends of bar 89 and obstruct its upward movement, whereby the feed horn 59 is maintained in its dotted line position until the counterweight 89 is manually released. After the counterweight is released the turning movement of the chain 86 upon the shaft 79 returns the counterweight to its uppermost position under the action of spring 88.

The feed horn 59 itself is adjustable to accommodate bats of different widths. The feed horn is constructed of two sections; viz., a section 97 fixedly secured to the base 71, and a section 98 adjustably mounted on the fixed section 97. The inner peripheries of the sections are semi-elliptical in cross-section, which when assembled, complement each other in forming a horn elliptical in cross-section. The concavities of the sections taper from the intake toward their smaller discharge ends, so as to form a longitudinally tapering passage having an intake opening 99 larger than the discharge or feed opening 101. The wider ends of the said horn sections are flared as at 102 so as to facilitate the insertion of the bat thereinto.

A stud 103 is pivotally secured into the top of the stationary feed horn section 97, said stud having a transverse threaded hole 104 therein. A complementary stud 106 is pivotally secured into the complementary section 98, said complementary stud having a slot 107 therein in registry with the hole 104.

An adjusting screw 108 is threaded into the hole 104. The screw has two collars 109 thereon so spaced as to be in abutting relation to the opposite sides of the stud 106 when the screw 108 is inserted into the slot 107. The action of the collars 109 prevents the axial movement of the screw 108 relatively to the stud 107; hence when the adjusting screw 108 is screwed outwardly of the hole 104 it moves the section 98 away from the section 97. This outward movement of the section 98 is pivoted around a bolt 111, which extends through tapered apertures 112 in respective flanges 113 disposed adjacent to the intake or flared ends of the sections 97 and 98. The head and the nut on the bolt 111 are evenly spaced from the respective flanges 113, and the bolt is resiliently held in position by springs 114 bearing upon the outer faces of the flanges 113 and upon the head and the nut at the ends of the bolt 111. The wider ends of the apertures 112 are opposite each other so that the bolt 111 is permitted to swing into the dotted line position shown in Figure 7.

While the adjusting screw 108 is operated, moving the section 98 around the pivot bolt 111, the screw 108 also changes its angular relation to the stationary section 97, and the movement of the adjusting screw 108 is made possible by the turning of the studs 103 and 107 around their vertical axis. The intake opening 99 is sufficiently wide to accommodate bats of various widths; it is the feed horn discharge opening which must be adjustable. By the aforesaid adjustment, not only the opening 101 is adjusted to the required size, but also the corresponding taper from the intake to the discharge end of the horn is made uniform.

After the roll is completed, the clutches 31

and 32 are moved against the action of the spring 38 into the position indicated in dotted lines in Figure 6, by the rocking of arms 34 on their pivots. Then the roll is removed from the drums 22 and 23 and is transferred between the drum 23 and an auxiliary drum 116, the latter being journaled on the frame 6 and is driven through a sprocket 118 on the drum 23 connected by a chain belt to a sprocket chain 117 on the stub shaft 21 on the end of the drum 116. The drum 116 rotates in the same direction as the drums 22 and 23, consequently the roll of bat positioned on the drums 23 and 116 will be rotated in the direction of its winding, whereby the winding of the roll is tightened.

In operation, the reeling mechanism is positioned in operative relation to the discharge end of the batting machine, and the transmission 8 is adjusted so as to rotate the winding mechanism of the reeling machine in synchronism with the batting machine, whereby any undue stress as well as excessive lagging of the bat passing from the batting machine into the reeling machine is obviated.

The bat is fed through the properly adjusted feed horn 59, to the drum 22, thereby drawn between the drum 22 and the reel tube 30, and is wound on the tube 30, which tube is supported by the clutches 31 and 32. The rotation of one of the clutches 32 causes the reciprocal travel of the feed horn 59 in parallelism with the reel tube 30 whereby the bat is wound spirally on the reel. The increasing diameter of the roll formed on the reel during winding gradually lifts the clutches 31 and 32 and thereby automatically adjusts the feed horn 59 upwardly and outwardly away from the tube 30 in proportion to the increase of the roll diameter, maintaining substantially the same clearance between the feed horn 59 and the periphery of the bat roll at all times while the bat is being wound.

The catching of the counterweight 89 by the dogs 93 secures the feed horn 59 in its extreme outward adjustment and also holds the tube 30 in its uppermost position. The completed bat roll is then removed and transferred to drum 23 and auxiliary drum 116, and it is there further rotated in the direction of the winding thereof until finally removed from the machine. The releasing of the counterweight 89 returns the feed horn 59 and the tube 30 to their initial position.

It will be recognized that after the initial speed adjustment, the machine does not require any careful adjustment or setting up. The spiral winding of the bat is accomplished automatically and uniformly throughout the entire length of the reel. The machine accomplishes this automatic feed adjustment through the revolving of the tube 30 by the engagement of the bat roll with drums 22 and 23. It is simple in construction, and lends

itself to effective application by the labor ordinarily available.

Having thus described the invention what I claim is:

1. The combination in a reel of positively driven drums adapted to contact with and rotate a reel tube, a feed horn support, a feed horn movably related to the support, sprocket and chain traverse mechanism for imparting reciprocal movement to the feed horn in parallelism with the axis of the reel tube while simultaneously urging the feed horn on its support away from the tube at a constant and uniform rate of movement.

2. The combination in a reel of positively driven drums adapted to contact with and rotate a reel tube, a feed horn support, a feed horn movably related to the support, means for moving the horn with relation to the support, sprocket and chain traverse mechanism for imparting movement to the feed horn at an angle to the horizontal plane of the axis of the reel tube and away therefrom.

3. The combination in a reel of positively driven drums adapted to contact with and rotate a reel tube, a feed horn support, a feed horn movably related to the support, means for moving the horn with relation to the support, sprocket and chain traverse mechanism for imparting reciprocal movement to the feed horn in parallelism with the axis of the reel tube and speed variable mechanism for synchronizing the rate of travel of the feed horn with the velocity of the tube.

4. A bat reeling machine comprising a plurality of rotatable drums rotatable at a constant and identical velocity, a reel tube frictionally engaging the peripheries of the drums, a power transmission for rotating the drums comprising split sheaves, a sprocket carried by one of the sheaves and two spaced apart sprockets carried by each of the drums, a sprocket chain passing over the sprocket sheave and a sprocket on one of the drums, sprocket and chain connections between the drums and a chain belt operatively connecting the sheaves with one of the drums.

5. A bat reeling machine comprising a main supporting frame, a reel tube support capable of vertical reciprocal movement with relation to the supporting frame, a feed horn support, a feed horn adjustably supported by the support, means for moving the horn with relation to the support, a reel tube contacting with the drums and means for automatically adjusting the feed horn on the support with relation to the axis of the reel tube, means for feeding a material to the reel.

6. A bat reeling machine comprising a main supporting frame, drums rotatably journaled in the frame and lying in the same approximate horizontal plane, a reel tube

support capable of reciprocal movement toward and away from the drums, a reel tube supported thereby and normally in frictional engagement with the drums, a feed horn 5 capable of reciprocal movement parallel with the axis of the reel tube and spaced therefrom, and means for moving the feed horn toward and away from the reel tube in a plane at an angle to the horizontal plane of the axis of the reel tube.

7. A bat reeling machine comprising a main supporting frame, drums rotatably journaled in the frame and lying in substantially the same horizontal plane, a reel tube 15 support capable of reciprocal vertical movement with relation to the supporting frame, a reel tube supported by the support and in contact with the drums and means for automatically securing the reel tube support at 20 the limit of its upward movement.

8. A bat reeling machine comprising a supporting frame, drums rotatably journaled in the frame, means for rotating the drums, a reel tube capable of vertical reciprocal 25 movement with relation to the drums, a feed horn, means for imparting reciprocal movement to the feed horn longitudinally of the axis of the reel tube, a rock shaft operatively related to the horn for moving the horn 30 away from the tube in synchronism with the upward movement of the tube, the rock shaft being rocked by such movement.

9. In a bat reeling machine comprising rotatable drums driven at a constant and like 35 velocity, a reel tube in frictional engagement with the drums, traverse mechanism for imparting reciprocal movement to a feed horn in alignment and spaced from the axis of the reel tube and instrumentalities for synchronizing the rate of travel of the feed 40 horn, the velocity of the reel tube and the outward and upward movement of the feed horn therefrom.

10. A bat reeling machine comprising a 45 main supporting frame, a reel tube support capable of reciprocal movement with relation to the supporting frame and comprising a suspended yoke having means engaging the ends of a reel tube, rotatable drums supported by the supporting frame, a reel tube supported by said reel tube support and contacting with the drums, a feed horn adjustably mounted on a support, means for automatically adjusting the feed horn on its support 55 with relation to the axis of the reel tube by means cooperating with said reel tube and reel tube support.

11. A bat reeling machine comprising a main supporting frame, a reel tube support 60 capable of reciprocal movement with relation to the supporting frame and comprising an inverted yoke suspended by means cooperating with a reel tube, rotatable drums supported by the supporting frame, a reel tube 65 movably mounted in the reel tube support

and supported by the drums, a feed horn and a support therefor, means for moving the horn on its support away from the reel tube at an angle to the horizontal plane of the axis of the reel tube.

12. A bat reeling machine comprising a main supporting frame, a reel tube support capable of reciprocal movement with relation to the supporting frame, rotatable drums supported by the supporting frame, a reel tube supported by the reel tube support and contacting with the drums, means for moving the horn on its support away from the reel tube at an angle to the horizontal plane of the axis of the reel tube and spring means 75 for urging the horn toward the axis of the reel tube.

13. A bat reeling machine comprising a supporting frame, drums rotatably journaled in the frame, means for rotating the drums, a reel tube capable of vertical reciprocal movement with relation to the drums and adapted to contact therewith, a feed horn, means for imparting reciprocal movement to the feed horn longitudinally of the axis of the reel tube, a rock shaft operably related to the horn for moving the horn away from the tube in synchronism with the upward movement of the tube, the rock shaft being rocked by such movement, and spring 85 means for urging the horn toward the reel tube.

14. A bat reeling machine comprising a supporting frame, drums rotatable in the frame, means for rotating the drums, split sheaves for varying the speed of rotation of the drums, a reel tube capable of vertical reciprocal movement with relation to the drums and adapted to contact therewith, a feed horn, means for imparting reciprocal movement to the feed horn longitudinally of the axis of the reel tube, a rock shaft operably related to the horn for moving the horn away from the reel tube in synchronism with the upward movement of the reel tube, the rock shaft being rocked by such movement, and means for urging the horn toward the tube.

15. In combination, spaced, uni-directionally rotating parallel drums and a support therefor, a feed horn support spaced from and traveling parallel to the axis of said drums, a feed horn mounted on said support and adjustable transversely of the axis of said drums, a reel tube supported and rotated by said drums, and means cooperating with said reel tube for actuating said feed horn support and said feed horn.

16. In combination, spaced, uni-directionally rotating parallel drums and a support therefor, a feed horn support spaced from, and slidably mounted on a track parallel to the axis of, said drums, a feed horn slidably mounted on said support and movable transversely of said track, a reel tube supported 125

on said drums, reciprocal driving means for said support actuated by rotation of said reel tube, said feed horn being moved transversely on said support by means cooperating with said reel tube and actuated by change in diameter of the reel.

17. In combination, spaced, uni-directionally rotating parallel drums, guides parallel to the axis of said drums and spaced therefrom, a carriage slidably on said guides, a bat guide mounted on said carriage and adjustable transversely relative to the track, means for driving said carriage in alternate directions, actuated by means cooperating with a reel tube, said reel tube frictionally cooperating with said drums, said driving means coincidentally cooperating with means for retracting said bat guide, said retracting means being actuated by change in diameter of the reel, and a support for said mechanism.

18. In combination, spaced, uni-directionally rotating parallel, positively driven drums, a bat guide movable longitudinally and transversely relative to the axis of said drums, a reel tube frictionally cooperating with said drums, through an interposed bat, longitudinal driving means for said bat guide actuated by rotative means cooperating with said reel tube, the transverse movement of said bat guide being controlled by said reel tube and bat disposed thereon, forming a reel, said bat guide being resiliently advanced, and positively retracted coincident with increase in the diameter of said reel, said driving means being adapted to reverse the direction of travel of said bat guide at predetermined points.

19. In combination, a frame, a plurality of spaced, unidirectionally driven, parallel drums, a reel tube supported and frictionally rotated by a pair of said drums, a bat guide slidably secured for longitudinal and transverse movement relative to said reel tube, driving means for longitudinal movement adapted to alternate the movement thereof, said transverse movement being resiliently advanced, and means cooperating with said reel tube for actuating said driving means and for providing retractive movement to said guide, and means for driving said drums.

20. In combination, a support or frame, a plurality of spaced, uni-directionally driven, parallel drums, a reel tube supported and frictionally rotated by a pair of said drums, guide members parallel to said drums and spaced therefrom, a carriage slidably secured on said guide members, driving means for said carriage adapted to reverse the direction of movement thereof at predetermined points, a feed horn slidably secured on said carriage, resilient means for advancing said feed horn toward said reel tube, positive means for retracting said feed horn, means cooperating with said reel tube for actuating said driving

means and said positive retractive means, and driving means for said drums.

21. In combination, a supporting frame, a plurality of spaced, uni-directionally driven parallel drums and driving means therefor, a reel tube supported and frictionally rotated by a pair of said drums, guide members parallel to said reel tube and spaced therefrom, a carriage slidably secured on said guide members, a feed horn slidably secured on said carriage and movable transversely of said guide members, a drive chain having a projecting pin cooperating with said carriage, said chain being mounted on sprockets and spanning the length of travel of said carriage, a lever cooperating with said feed horn for retracting movement thereof, resilient means for advancing said feed horn, and means cooperating with said reel tube for actuating said sprockets and for retracting said horn.

22. In combination, a supporting frame, a plurality of spaced, uni-directionally driven, parallel drums and driving means therefor, a reel tube supported and frictionally driven by a pair of said drums, guide members spaced from and parallel to said reel tube, a carriage slidably secured on said guide members, a feed horn slidably secured on said carriage and adjustable transversely to the movement of said carriage, a drive chain cooperating with sprockets spaced to provide reciprocal travel of said carriage, a projecting pin on said chain cooperating with said carriage, means cooperating with said reel tube for driving said chain and for retracting said feed horn, said feed horn being resiliently advanced, and automatic means for maintaining said feed horn in retracted position, and releasing means therefor.

23. The combination in a reel of positively driven drums adapted to contact with and rotate a reel tube, a feed horn support, a feed horn movably related thereto, sprocket and chain traverse mechanism for imparting reciprocal movement to the feed horn support in parallelism with the axis of the reel tube, and means cooperating with the reel tube for simultaneously moving the feed horn with relation to its support.

In testimony whereof I affix my signature.

ALLISTER S. MITCHELL.
